[57] **CLAIM**

The ornamental design for a portable blower, as shown and described.

DESCRIPTION

FIG. 1 is a perspective view of a portable blower, showing our new design;

FIG. 2 is a side elevational view thereof; with the strap cut away for the convenience of illustration;

FIG. 3 is a top plan view thereof;

FIG. 4 is a bottom plan view thereof;

FIG. 5 is a front elevational view thereof;

FIG. 6 is a rear elevational view thereof;

FIG. 7 is another perspective view, with the strap and attachment means removed;

FIG. 8 is a side elevational view of the second embodiment;

FIG. 9 is a partial side elevational view thereof; and

FIG. 10 is a partial front elevational view thereof.

FIG. 1

FIG. 2
